UNITED STATES PATENT OFFICE.

LUIGI TROUBETZKOY, OF MILAN, ITALY.

APPARATUS FOR GENERATING ACETYLENE GAS.

SPECIFICATION forming part of Letters Patent No. 614,906, dated November 29, 1898.

Application filed July 8, 1897. Serial No. 643,844. (No model.)

To all whom it may concern:

Be it known that I, LUIGI TROUBETZKOY, a subject of the King of Italy, residing at Milan, in the Kingdom of Italy, have invented certain new and useful Improvements in Apparatus for Generating Acetylene Gas, of which the following is a full and complete specification, such as will enable those skilled in the art to which it appertains to make and use the same.

This invention relates to apparatus for generating acetylene gas; and the object thereof is to provide an improved apparatus of this class which is simple in construction and operation and wherein the calcic carbid which is employed for the generation of the gas is subdivided or placed in separate receptacles, one above the other, whereby I do away with the great inconvenience of an undivided charge of this material, which can only with great difficulty be made to yield all the acetylene gas it is capable of producing when not separated in this manner by reason of the fact that when subjected to the action of water a crust of lime forms thereon, which tends to prevent further contact between the water and the calcic carbid. By this arrangement an estimate may also be made with almost absolute accuracy of the volume of gas produced from the calcic carbid, with the result that the gasometer is invariably capable of containing all the gas evolved without subjecting it to undue pressure, and by means of this arrangement it is impossible that there should ever be a production of gas for which there would not be abundant room in the gasometer, which is a serious objection to apparatus of this class as usually constructed, in which there is a constant danger that the gasometer may become overcharged.

A further advantage of my construction consists in the automatic devices which I employ for controlling the flow of the water which is admitted to the calcic carbid in the generator and in the use of a hydraulic seal for the generator, which feature renders it possible to recharge the generator without interfering with or suspending the operation of illumination, it being merely necessary to close a valve in a pipe which connects the generator with the gasometer in order to recharge the generator.

A further advantage of my improved apparatus consists in the simplicity of its construction, whereby it is possible for any one to make and operate the same or manage it when constructed, and the invention is fully disclosed in the following specification, of which the accompanying drawings form a part, in which the separate parts of my improved apparatus are designated by the same numerals of reference in each of the views, and in which—

Figure 1 is a side view of said apparatus, and Fig. 2 a section on the line 2 2 of Fig. 1.

In the practice of my invention I provide a gasometer which consists of the usual cylindrical casing or receiver 5, which is filled or partially filled with water in the usual manner and in which is placed a vertically-movable pressure-drum 6, which is open at the bottom and closed at the top and which is provided with the usual guide-rollers 7 and one or more counterbalance-weights 8, which are passed over suitable pulleys 9 and connected with said drum, as shown at 10. All these features of construction, however, are the same as those usually employed and form no part of this invention.

In the construction of the generator I employ a cylindrical casing 11, which is provided near its lower end with a transverse partition-plate 12 and in which is placed a tubular receptacle 13, which is open at the top and closed at the bottom and between which and the cylindrical casing 11 is an annular chamber 14. I also employ a supplemental tubular receptacle 15, which is closed at the bottom and open at the top, and placed in the tubular receptacle 15 is a plurality of small cylindrical boxes or receptacles, which, as shown in the drawings, are four in number and which are designated by the reference-numerals 16, 17, 18, and 19, and these boxes or receptacles decrease in size from the bottom upwardly, and the box or receptacle 18 is so formed as to enter or rest upon the top of the box or receptacle 19, the box or receptacle 17 in the top of the box or receptacle 18, and the upper box or receptacle 16 in the top of the box or receptacle 17, and each of the boxes or receptacles 16, 17, and 18 is provided near the top thereof with an annular row of perforations 20.

The cylindrical casing 11 is enlarged at the top, so as to form an annular chamber 21, and the said casing and said annular chamber 21 are adapted to be filled with water.

5 The second part of the generator consists of a tubular casing 22, which is provided at or near the middle portion thereof with a partition-plate 23, by means of which a water-receptacle 24 is formed, and the lower end of the casing 22 is open and is adapted to enter the annular chamber 14 between the tubular receptacle 13 and the cylindrical casing 11, and said water-receptacle 24 is provided with a removable cover 25 and at each side thereof 15 with handles 26, and the casing 22, in which the water-receptacle 24 is formed, is supported in the position shown in Fig. 2 by side arms or brackets 27, which are secured thereto and which rest on the bottom of the 20 annular chamber 21. I also provide a pipe 28, which is bent transversely of the casing 22 and both ends of which are passed therethrough into the water-receptacle 24, and one end of this pipe is passed downwardly through 25 the center of the partition-plate 23, which constitutes the bottom of the water-receptacle 24 and is provided with a discharge-nozzle 29, which terminates directly over the box or receptacle 16, and placed in the pipe 28, 30 outside of the casing 22, is a valve 30, with which is connected a lever 31, the outer end of which is weighted, as shown at 32, and the inner end of which is provided with a curved arm 33, which is adapted to be operated by a 35 rod 34, which is secured to the top of the drum 6 and which is provided with an arm 35.

Extending from at or near the top of the receptacle 13, within the cylindrical casing 11 of the generator, is a pipe 36, which extends through the annular chamber 14 and through the bottom 12 of the cylindrical casing 11 and out through the side thereof, as shown at 37, and this pipe 36 connects with a condenser 38 of any preferred form, which is provided at one side with a pipe 39, through which the water of condensation and other material may be drawn off, and this pipe 39 is provided with a valve 40, and a pipe 41 is connected with the end of the condenser 38 45 opposite that with which the pipe 36 communicates, and the pipe 41 passes into the bottom of the gasometer and connects with an upright pipe 42, placed therein in the usual manner, said pipe 42 being shown in dotted lines in Fig. 1, and the pipe 41 is provided with a valve 43.

The pipe 42 constitutes the supply-pipe of the gasometer, and I also provide a discharge-pipe 44, which is also shown in dotted lines 60 in Fig. 1, and with the lower end of which is connected a pipe 45, which extends through the bottom of the gasometer and in which is placed a valve 46, the pipe 45 being intended as a supply-pipe by means of which the gas 65 is conveyed from the gasometer to the mains or pipes for use.

The boxes or receptacles 16, 17, 18, and 19

are supported one above the other in the generator in any desired manner, and the tubular receptacle 15 is removable, and whenever 70 it is desired to charge the generator the upper portion, which consists of the casing 22, is removed, and the tubular receptacle 15 is also removed, and the boxes or receptacles 16, 17, 18, and 19 are separated and filled or partially 75 filled with calcic carbide, and whenever it is desired to operate the apparatus the casing 22, containing the water-receptacle 24, is placed in position and said receptacle is filled or partially filled with water. The valve 43 in the 80 pipe 41 is then opened and the water flows through the pipe 28 into the upper box or receptacle 16, and this flow may be regulated by the nozzle 29 as may be desired.

The gas is generated by the water coming 85 in contact with the calcic carbide in said box or receptacle 16 and passes through the tube 36 into the gasometer, and the water will continue to flow through the pipe 8 until the drum 6 of the gasometer rises, so as to operate the lever 31 and cut off the flow of the water, and when said drum sinks to a predetermined position said lever will be operated, the valve 30 will be opened, and the flow of water will be recommenced. By the time the 95 box or receptacle 16 is filled with water the calcic carbide therein will have lost its strength or be exhausted and the water will flow out through the perforations 20 in the top thereof or over the top thereof and down into the 100 box or receptacle 17, and this operation will be continued until the entire charge of the calcic carbide is exhausted.

As long as there is calcic carbide in the generator the production of gas will be uniform 105 and the top of the drum 6 will not fall more than about six inches above the level of the water in the receiver 5, and when the drum falls more than this amount it is a very evident sign that the calcic carbide is exhausted. 110

In order to recharge the generator, the lever 31 is turned so that it will stand vertical and be free from the spring 25 of the rod 34, which is connected with the drum 6, and this operation cuts off the flow of the water. The 115 valve 43 is then closed and the valve 40 opened in order that the air may pass, so as to fill the vacuum which is caused by lifting or removing the casing 22. Said casing 22 is then lifted or removed and the generator is again 120 recharged, as hereinbefore described, after which the separate parts of the generator are again connected, and the apparatus is ready for operation, the valves 39, 43, and 46 being manipulated, as will be readily understood. 125

My improved apparatus is simple in construction and operation, and it will be apparent that the apparatus may be made of any desired capacity, the capacity of said apparatus depending entirely on the size of 130 the generator.

It will be apparent that many changes in and modifications of the construction herein described may be made without departing

from the spirit of my invention or sacrificing its advantages, and my invention is not therefore limited to the construction, combination, and arrangement of the separate parts thereof as herein shown and described.

Having fully described my invention, I claim as new and desire to secure by Letters Patent—

1. In an acetylene-gas generator constructed as herein described, a plurality of boxes arranged one above another, said boxes being open at the top and closed at the bottom, and increasing in size from the top box downwardly, and said boxes being adapted to receive calcic carbid, substantially as shown and described.

2. In an apparatus for generating acetylene gas, the combination with a gasometer, of a generator consisting of a casing which is open at the top, a receptacle placed therein which is also open at the top, a plurality of boxes placed in said receptacle, one above the other, and each of which is open at the top and closed at the bottom, said boxes being each adapted to receive a charge of calcic carbid, and means for feeding water into the upper box, and means for conveying the gas into the gasometer, said boxes decreasing in size from the bottom box upwardly, whereby the water is adapted to flow from the upper box into each of the lower boxes successively, substantially as shown and described.

3. In an apparatus for generating acetylene gas, the combination with a gasometer, of a generator consisting of a casing which is open at the top, a receptacle which is placed therein, and also open at the top, a plurality of boxes or receptacles mounted in said first-named receptacle, one of which is placed above the other, and said boxes or receptacles decreasing in size from the bottom upwardly, a water-receptacle, consisting of a casing which is provided with a transverse partition and the lower end of which is open, said open lower end being adapted to be inserted into said casing, and to inclose said receptacle, and devices for feeding the water into said boxes or receptacles, and for conveying the gas into the gasometer, substantially as shown and described.

4. In an apparatus for generating acetylene gas, the combination with a gasometer, of a generator consisting of a casing which is open at the top, a receptacle which is placed therein, and also open at the top, a plurality of boxes or receptacles mounted in said first-named receptacle, one of which is placed above the other, and said boxes or receptacles decreasing in size from the bottom upwardly, a water-receptacle, consisting of a casing which is provided with a transverse partition and the lower end of which is open, said open lower end being adapted to be inserted into

said casing, and to inclose said receptacle, and devices for feeding the water into said boxes or receptacles, and for conveying the gas into the gasometer, the devices for feeding the water being operated by the vertically-movable drum of the gasometer, substantially as shown and described.

5. In an apparatus for generating acetylene gas, the combination with a gasometer, of a generator connected therewith by means of a pipe, said generator consisting of a bottom casing, and a removable upper portion, in which is formed a water-chamber the lower end of the removable upper portion being open and adapted to enter said bottom portion, a removable receptacle which is open at the top, and adapted to be inserted into said bottom portion, and a plurality of boxes which are placed in said receptacle one above the other, and each of which is open at its upper end, and means for feeding water into said boxes or receptacles, substantially as shown and described.

6. In an apparatus for generating acetylene gas, the combination with a bottom casing, which is open at the top, and an upper casing which is provided with a transverse partition, and which is open at the bottom, and adapted to enter said bottom casing, said bottom casing being also provided with a receptacle which is open at the top, a supplemental receptacle which is placed therein, and also open at the top, and a plurality of boxes placed in said supplemental receptacle one above the other, each of said boxes being open at the top and being adapted to receive calcic carbid, and means for feeding water into the upper box, and for allowing it to flow into each successive box, substantially as shown and described.

7. In a gas-generator, the combination of a bottom receptacle which is open at the top, an upper receptacle which is open at the bottom and provided with a transverse partition whereby a water-chamber is formed in the upper part thereof, a receptacle which is placed in the bottom portion of the generator, and open at the top, and a supplemental receptacle placed therein, and open at the top, and a plurality of boxes which are adapted to receive calcic carbid, said boxes being placed in said supplemental receptacle, and means for feeding water into said boxes, substantially as shown and described.

In testimony that I claim the foregoing as my invention I have signed my name, in presence of the subscribing witnesses, this 1st day of April, 1897.

LUIGI TROUBETZKOY.
